UNITED STATES PATENT OFFICE.

CARL LOIBL, OF MUNICH, GERMANY.

HORSESHOE-CALK.

No. 823,423.

Specification of Letters Patent.

Patented June 12, 1906.

Application filed October 10, 1905. Serial No. 282,100.

To all whom it may concern:

Be it known that I, CARL LOIBL, a citizen of Germany, residing at Munich, Bavaria, Germany, have invented certain new and useful Improvements in Horseshoe-Calks; and I do hereby declare the following to be a full, clear, and exact description of the invention, such as will enable others skilled in the art to which it appertains to make and use the same.

The present invention relates to calks for horseshoes, which even after a strong wear have narrow tread-surfaces only and in which nevertheless any breakage of single parts and any clenching of dirt or soil, snow, and ice in the interior of the cavities is rendered impossible.

In the accompanying drawings, which represent the new calk for horseshoes, Figure 1 is a perspective view; Fig. 2, a side view, and Fig. 3 a section on line A B of Fig. 2.

In the body *a* of the calk, which is provided with the screw *b*, is arranged a canaliculated cavity or gutter *c*, leaving at the lower side of the calk only two narrow surfaces *d e*. The body *a* of the calk further possesses a bore *f*, crossing the cavity *c* rectangularly and being so arranged that it penetrates the cavity *c*. This opening or bore *f* has at its two ends widenings forming beveled surfaces *g* and being directed so as to penetrate the upper side of the calk. By this means a rela-

tively narrow bridge *h* is formed. In consequence of this arrangement of the cavities *c* and *f* dirt and snow or ice which may have entered these cavities are pressed out automatically at each step of the horse at the upper part of the body *a* of the calk, while any stoppage of the cavities and forming of slippery surfaces is efficiently prevented.

As will clearly be understood, after a certain wear of the tread-surfaces in place of the two narrow surfaces *d e* at the lower side of the calk four small surfaces are formed by degrees at the four corners of the body *a*, and after the wear of these four small surfaces two narrow surfaces are at last formed, crossing rectangularly the worn original surfaces *d e*.

Having thus described my invention, what I claim, and desire to secure by Letters Patent, is—

A calk for horseshoes having at its lower side a canaliculated cavity or gutter *c* leaving two narrow tread-surfaces *d e* and a bore *f* crossing and penetrating said cavity, and widenings of said bore forming beveled surfaces *g*.

In testimony whereof I hereunto affix my signature in the presence of two witnesses.

CARL LOIBL.
